(57) **CLAIM**

The ornamental design for a wire stripper with thumb recess, as shown and described.

DESCRIPTION

FIG. 1 is a front side perspective view of a wire stripper, according to a first example embodiment of the present invention.

FIG. 2 is a front view of the wire stripper shown in FIG. 1. FIG. 3 is a back side view of the wire stripper shown in FIG. 1.

FIG. 4 is a left side view of the wire stripper shown in FIG. 1.

FIG. 5 is a right side view of the wire stripper shown in FIG. 1.

FIG. 6 is a top view of the wire stripper shown in FIG. 1. FIG. 7 is a bottom view of the wire stripper shown in FIG. 1; and,

FIG. 8 is a back side perspective view of the wire stripper shown in FIG. 1.

The broken lines are included for the purpose of illustrating an environment, and form no part of the claimed design. The inventor anticipates that the invention can be any part, portion, element, or combination of elements of the depicted design.

1 Claim, 4 Drawing Sheets
